UNITED STATES PATENT OFFICE

146,072

DESIGN FOR AN AIRPLANE

Herbert L. Bowers, Kenmore, N. Y., assignor to
Bell Aircraft Corporation, Buffalo, N. Y.

Application March 14, 1945, Serial No. 118,485

Term of patent 14 years

(Cl. D71—1)

To all whom it may concern:

Be it known that I, Herbert L. Bowers, a citizen of the United States, residing at Kenmore, in the county of Erie and State of New York, have invented a new, original, and ornamental Design for an Airplane, of which the following is a specification, reference being had to the accompanying drawing, forming part thereof.

In the drawings:

Fig. 1 is a front elevational view of an airplane showing my new design as it appears with the landing gear in retracted condition;

Fig. 2 is a top plan thereof; and

Fig. 3 is a side elevational view thereof.

I claim:

The ornamental design for an airplane, as shown and described.

HERBERT L. BOWERS.
